RACK FOR COLLETS OR THE LIKE

Daniel S. Marselli, 99 West St.,
Cromwell, Conn. 06416

Filed May 6, 1968, Ser. No. 11,792

Term of patent 14 years

Int. Cl. D6—01

U.S. Cl. D33—17

FIG. 1

FIG. 2

FIG. 3

FIG. 4

FIG. 1 is a side elevational view of a rack for collets or the like embodying my new design;

FIG. 2 is a top view thereof;

FIG. 3 is a front view thereof; and

FIG. 4 is a bottom view thereof.

The broken line showing of a collet in FIG. 1 is for illustrative purpose only.

I claim:

The ornamental design for a rack for collets or the like, as shown and described.
